Primary Examiner — Richard Kearney*(74) Attorney, Agent, or Firm* — Reilly Intellectual Property Law Firm(57) **CLAIM**

The ornamental design for a magnetic zipper, as shown and described.

DESCRIPTION

FIG. 1 is a side view showing our design;

FIG. 2 is a front view of FIG. 1;

FIG. 3 is an opposite side view of FIG. 1;

FIG. 4 is a top view of FIG. 2;

FIG. 5 is a bottom view of FIG. 2; and,

FIG. 6 is an enlarged view of the area demarcated in FIG. 5. The dot-dot-dash broken lines shown in FIGS. 5 and 6 demarcate the enlarged view shown in FIG. 6 and form no part of the claimed design. The broken line portion of FIGS. 1, 2, 3, 4 and 5 is included to show environment that forms no part of the claimed design.
